UNITED STATES PATENT OFFICE.

WILLIAM WENDERHOLD, OF NEW YORK, N. Y., ASSIGNOR, BY MESNE ASSIGNMENTS,
TO CRU PATENTS CORPORATION, A CORPORATION OF NEW YORK.

FILM-REEL.

1,360,838.

Specification of Letters Patent. Patented Nov. 30, 1920.

Application filed April 8, 1918. Serial No. 227,412.

To all whom it may concern:

Be it known that I, WILLIAM WENDERHOLD, a citizen of the United States, residing at New York, in the county and State of New York, have invented certain new and useful Improvements in Film Reels, of which the following is a clear, full, and exact description.

This invention relates to an improvement in film reels, such as are employed in motion picture apparatus, to carry a roll of picture film.

The object of my invention is to provide a film reel to which the end of a film can be attached very quickly and in the proper direction.

Another object is to provide a construction which is easily accessible for the threading of a film.

Another object is to provide a hub insert with a plurality of key-slots to increase the opportunity of catching the key on the reel shaft when the reel is being mounted.

Another object is to provide a construction that will make the reel rigid and still fit the machines and apparatus now in use.

Another object is to provide an easily de-mountable structure so that each part of the reel can be renewed when worn.

Referring to my drawings:

Figure 1 is a side elevation, partly in cross-section.

Fig. 2 is a cross-section through the reel.

Fig. 3 is an outside view.

Fig. 4 is a partial side view.

As shown in Fig. 1, the side plates 1 and 2 are fastened to the hub members 3 and 4, by the male and female screw-bolts 5 and 6. The hub members 3 and 4 are fastened together by the male and female screw-bolts on to the steel insert 9. This insert is provided with six key-slots on each end to receive the usual key 10 on the reel supporting shaft 11.

On the hub members 3 and 4 are mounted three springs 12, 13 and 14, and one member springs point in one direction thereon and in the opposite direction on the other member (see Fig. 3) so that the film can be engaged thereby in one direction only from the side nearest to the operator, and these springs are provided with little projections XX, by means of which projections these said

springs can be lifted from the outside of the reel when a film is being slipped under the spring. The projections XX on the spring extend through the spokes of the plates 1 and 2 and a little slot 1^a in the spokes limits the amount that each spring can be lifted to prevent the straining of the spring.

The construction of the reel being such as to contain only three spokes makes the hub easily assessible. The side-plates, 1 and 2, may be of heavy material without materially increasing the weight of the reel, and the edges of the plates can be a perfect radius to prevent injury to the film.

The hub-members 3 and 4, when mounted together are of standard width so as to be attachable to existing standard reel shafts, the side plates 1 and 2 being extended over the standard width at a point where they cannot interfere with the standard dimensions of a film apparatus.

While I have shown and described a specific structure embodying the principles of my invention, I wish it to be understood that my invention in its broad scope as defined by the claims is not to be limited or restricted thereto, as many changes in details of construction will readily appear to those skilled in the art without departing from the contemplated spirit and scope of my invention:

What I claim as my invention is:

1. In a film reel, a hub of standard width, side plates fastened thereto, and said side plates extending beyond the width of the hub, said side plates having spokes and each of said spokes having a notch, a spring fastened to the hubs and extending through the notches, one set of said springs pointing in one direction and the other set in the opposite direction, said notches limiting the movement of the springs.

2. In a film reel, a hub, side plates secured thereto, said side plates having radiating spokes, said hub having a set of springs on the periphery thereof adjacent each spoke, the springs of each set being secured to the hub at their respectively opposite ends whereby the free ends of said springs point in opposite directions with respect to each other.

3. In a film reel, a hub having springs on the periphery thereof, said springs being arranged in sets and the members of each set

being secured to the hub at respectively opposite ends and having their free ends disposed in opposite directions with respect to each other.

5. 4. In a film reel, a hub composed of sections, an insert arranged intermediate said sections and to which said sections are secured, side plates secured to said hub and

spring clamping devices mounted on the periphery of said hub between the side 10 plates.

Signed at the city, county, and State of New York this sixth day of April, one thousand nine hundred and eighteen.

WILLIAM WENDERHOLD
